UNITED STATES PATENT OFFICE.

JOHN CAMPBELL McINTOSH, OF THE GLEN, BY PAISLEY, SCOTLAND, ASSIGNOR TO
WILLIAM HENRY ALEXANDER AND JOHN LIDDLE, BOTH OF GLASGOW, SCOTLAND.

VALVE FOR INTERNAL-COMBUSTION ENGINES.

1,211,202.

Specification of Letters Patent.

Patented Jan. 2, 1917.

Original application filed December 20, 1909, Serial No. 534,168. Divided and this application filed January 16, 1913. Serial No. 742,358.

To all whom it may concern:

Be it known that I, JOHN CAMPBELL McINTOSH, a subject of the King of Great Britain, residing in Glenhall, The Glen, by Paisley, Scotland, have invented certain new and useful Improvements in Valves for Internal-Combustion Engines, of which the following is a specification.

This application relates to improvements in valves for four cycle internal combustion engines and constitutes a division of my co-pending application, Serial Number 534,168, filed December 20, 1909.

As disclosed in my said prior application my improved engine comprises two reciprocating cylindrical sleeve valves arranged concentrically with the working cylinder and my present application relates particularly to the construction of such cylinder and valve sleeves whereby the friction incidental to the working of the valves is materially reduced, the lubrication of the valve sleeves is improved, and all parts of the valve sleeves and their operating connections, as well as the working piston, are readily accessible for adjustment or repairs.

In the accompanying drawings I have illustrated a preferred embodiment of my invention and in the said drawings, Figure 1 is a vertical longitudinal sectional view through the cylinder of one form of my improved motor; Fig. 2 is a transverse vertical sectional view at right angles to Fig. 1. Fig. 3 is a view similar to Fig. 1 but showing the cylinder-head and the valve sleeves with their operating devices removed from the cylinder; Fig. 4 is a view similar to a portion of Fig. 1 but showing a slightly modified apparatus, and Fig. 5 is a detail view which will be later described.

Referring now to the drawings, in which corresponding reference characters indicate corresponding parts throughout all the views, and particularly to Figs. 1, 2, and 3, A indicates the main shaft mounted in the usual manner in the crank case V of the motor. The cylinder of the motor comprises a lower portion having a water jacket R inclosing a liner M supported on a shoulder M³ which forms the working cylinder of the motor piston N. The inner wall of the water jacket R is offset from the upper part of the liner M forming an annular cavity U in which the valve sleeves G and

H reciprocate. Above the liner M is the 55 cylinder head D whose lower portion is of an external diameter equal to that of the liner and forms a gas-tight engagement with the liner at the point M' just above the ports O of the liner. Immediately below the 60 ports O the liner M is provided with compression rings Q and the cylinder head D is provided with similar rings P surrounding its lower end. The sleeves G and H have ports corresponding with the ports O of the 65 liner M and are of just sufficient length for their lower ends G³ and H³ to extend below the rings Q and their upper ends to project above the rings P. The valve sleeves G and H are provided with upward projections G' H' diametrically opposite from each other in the axial line of the main shaft A and their projections are provided with trunnions on which are pivoted respectively the connecting rods I, I, and J, J, 75 for reciprocating the valve sleeves from the valve operating shaft C. This shaft extends across the top of the cylinder parallel with the main shaft A and is mounted in bearings C¹ C² projecting upwardly from opposite sides of the cylinder head D adjacent the central depressed portion provided with the socket L, for the spark plug, and is provided immediately beyond its bearings with cranks E, E and F, F to which are attached 80 the connecting rods I, I and J, J of the valve sleeves G and H. For driving the shaft C from the main shaft I provide a vertical shaft B connected to the shafts A and C by suitable skew or other gearing A'. 90

The cylinder head D is coextensive at the top with the water jacket R, except on the sides where it is recessed as shown at K to provide a working space for the valve operating connections, and projects downwardly 95 around the valve sleeves as shown more particularly in Fig. 2, where it is joined to the open top of the water jacket at R², the water jacket being closed at the bottom of the recesses K as indicated at R'. For the 100 admission and exhaust of the explosive charge suitable ports Y and Z registering with the ports O of the liner are provided. For lubricating the valve sleeves the cavity U is maintained charged with oil and for 105 this purpose I connect the cavity with the crank case by means of suitable bores, indicated by the dotted lines W, which enter

the crank case at W'. The oil may be forced through these bores by a suitable force feed lubricator or fed directly to the cavity U and allowed to drain through the bores to 5 the crank case.

My improved motor operates on the well-known principle of prior sleeve valve engines, the valve sleeves coöperating on their reciprocation to open the exhaust port on 10 one up stroke of the piston and the intake port on the succeeding down stroke while maintaining both ports closed during the compression and working strokes. The advantages of my improved motor over the 15 ordinary construction of motors of this type will be obvious from the foregoing description and drawings. The liner M keeps the valve sleeves out of contact with the working piston and also keeps the hot gases out 20 of contact with the valve sleeves. The liner is in fixed metallic contact with the water jacket at both ends and cannot therefore become highly heated. Further, by connecting the liner with the cylinders at the bottom 25 and spacing the water jacket therefrom throughout its upper portion, an oil retaining well is formed so that the valve sleeves work in oil and are perfectly lubricated at all times. By this construction also the 30 valve operating connections may be attached to the top of the valves so that by forming the cylinder head detachable in the manner shown the entire valve mechanism may be removed as a unit as shown in Fig. 3. 35 For this purpose the shaft C is preferably made up of sections coupled together at their ends as shown at X, so that driving connections of the shaft need not be disturbed. By operating the valve sleeves from 40 the top instead of the bottom the length of the sleeves is materially reduced. Instead of having to extend into the crank chamber they need be no longer than necessary to properly engage the rings P and Q. 45 In Figs. 4 and 5 I have illustrated a slightly modified form of my improved motor. In this construction the liner M is extended to near the top of the cylinder head and carries both sets of compression rings 50 P' and Q'. By this construction the joint between the piston and liner within the

working portion of the valve sleeves is avoided.

Having thus described my invention what I claim as new and desire to secure by Letters Patent is:

1. In an engine of the class described, the combination of a cylinder, a liner therefor having its lower end in engagement with said cylinder, said cylinder being spaced 60 therefrom above, a valve mechanism comprising a sleeve surrounding said liner within said space, a cylinder head closing the top of said liner having a lower portion with an internal diameter equal to that of 65 the liner and coacting therewith to form a gastight engagement with the liner, and means carried by said cylinder head for operating said sleeve.

2. In an engine of the class described the 70 combination of a cylinder, a liner therefor having ports therein, a plurality of concentric valve sleeves surrounding said liner, said sleeves terminating a short distance below said ports and above the lower end of 75 said liner, the upper portion of one of said sleeves being offset laterally, and a crank engaging said offset portion for operating said valve sleeves.

3. In an engine of the class described the 80 combination of a cylinder, a cylindrical liner mounted in said cylinder with its inner surface forming a continuation of the bore of said cylinder, a detachable cylinder head closing the top of said liner and comprising 85 a portion having an exterior diameter equal to that of said liner, and a plurality of concentric valve sleeves mounted on said liner and cylinder head, one of said sleeves provided with a pair of diametrically disposed 90 upward projections constituting trunnions, and connecting rods pivotally connected to said trunnions for operating said valve sleeves.

In witness whereof, I have hereunto set 95 my hand at Glasgow, Scotland, this 24th day of December, 1912.

J. CAMPBELL McINTOSH.
